UNITED STATES PATENT OFFICE.

GEORGE L. ALLEN, OF WILMINGTON, NORTH CAROLINA.

SIDE BEARING.

1,084,522.

Specification of Letters Patent. Patented Jan. 13, 1914.

Application filed July 26, 1912. Serial No. 711,762.

To all whom it may concern:

Be it known that I, GEORGE L. ALLEN, a citizen of the United States, residing at Wilmington, in the county of North Hanover, State of North Carolina, have invented 5 certain new and useful Improvements in Side Bearings, of which the following is a description, reference being had to the accompanying drawings, forming a part 10 thereof.

My invention relates to an improved form of side bearing in which there is little or no friction between the moving parts and yet which retains to a large degree that ruggedness and simplicity which is so essential to 15 railway devices.

To this end my invention consists in certain novel features of construction which are clearly illustrated in the accompanying 20 drawing and described in the following specification.

In the drawing Figure 1 is a view in elevation with a portion of the casing removed, of an improved form of side bearing. Fig. 25 2 is an end view of the same. Fig. 3 shows a slightly modified form.

The side bearing is composed of three elements. An upper member 1 which is provided with a bearing surface 2 and side 30 walls 3, said side walls inclosing a cylindrical roller 4 which is to be regarded as the second element of the combination herein described. The roller 4 is interposed between the upper member 1 and a lower member 5 which latter member is provided with a suitable bearing surface 6 for the roller to travel over, said lower member being the third element of the aforementioned combination.

40 In order to more fully explain the various parts they will be taken up in order, in which the upper member 1, as illustrated in Figs. 1 and 2, is box like in construction and is composed of a top base plate 15, said base 45 plate provided with means whereby it may be attached to the body of the car, the under side of said base plate forms a bearing surface 2 for the roller 4 to travel on and has teeth like projections 7 extending therefrom. The side walls 3 of the upper member are provided with a longitudinal recess 8 in which the trunnions 9 of the roller 4 move. Entrance to the longitudinal recess 8 is provided at one end to allow for the 55 entrance of the roller for the assembling of the various parts. This entrance is formed

by cutting away a portion of the casing thereby forming the lip or ledge 10. The box-like construction of member 1 serves to keep the cylindrical roller in position and at 50 the same time protect it and prevent it from becoming clogged with dust and other objectionable material which would tend to mar the smooth working of the herein described bearing. The roller, as illustrated 55 in Figs. 1 and 2 is cylindrical in shape, and provided with tooth-like depressions 14 which are adapted to engage the projections or teeth 7 of the upper member, the roller, as illustrated herewith, is provided with 70 three of the above mentioned depressions which extend around the roller for approximately one-third of the circumference, diametrically opposed to the above mentioned depressions are teeth-like projections 12 75 which serve to coöperate with the lower member 5 upon which it rolls. Upon the outer edges of the cylindrical roller 4 and formed integral therewith are trunnions 9 cylindrical in shape and having a grooved 80 portion 11 as illustrated in Figs. 1 and 2, the purpose of these trunnions with their grooved portions being more fully taken up and described in a later paragraph of the 85 present specification.

The bottom plate 5, which has already been mentioned as the third element of the novel combination, consists of a plate having holes 13 arranged therein, said holes being tooth-like in form and arranged to engage the teeth 12 of the roller 4. In the present instance there being three such tooth-like depressions which correspond in number to the teeth 12 to the roller 4. The plate 5 is provided with means whereby it 90 may be attached to a truck and securely held thereto.

Taking up now the working of the present device the trunnions on the roller have been provided with grooved sides the object of 100 which is to allow the roller to be slid into position, the grooved side being upmost and passing beneath the lip 10 of the casing 3. The roller thus having been placed into position, the teeth and depressions of the various members operate in conjunction. The roller allows the upper and lower plate to shift their relative position with little or no friction, and should the above mentioned shifting be excessive the roller will take up 105 110 a position as shown in dotted lines in Fig. 1, and it is to be noted in this connection that

the trunnion will prevent the roller from leaving the housing and thus make it impossible for the accidental loss of said roller. Furthermore with the teeth arranged as shown should the car become derailed and the truck therefor subject to unusual turning the teeth will become disengaged as shown in the dotted position in Fig. 1 and locking between the car body and the truck is thereby rendered impossible. Further when the truck is moved horizontally back into its normal position after a derailment the teeth of the roller automatically reengage themselves without the necessity of jacking up the car. In the normal operation of the various parts the roller cannot leave the casing as the grooved side of the trunnions will not come in the proper position to pass beneath the lip 10, as can be seen by the dotted lines in Fig. 1.

The present invention may take a somewhat modified form as illustrated in Fig. 3 in which the plate and tooth-like projections and depressions on the plate have been arranged on the arc of a circle, the cylindrical roller is shown as having the form of a frustum of a cone and the depressions and projections have been reversed with regard to the upper and lower plates. Of course, this does not depart from the spirit of my invention and neither do I wish to limit myself to any special number of teeth but have merely shown three as illustrating an operative number.

Having thus fully described the construction and operation of my device what I claim to be new and original with me is:

1. In a side bearing, an upper member, a lower member, a roller interposed therebetween, positive means on the upper member, lower member and roller determining the relative positions of each, said upper member comprising a housing for the trunnions of the said roller, said housing having a limited entrance thereto, the trunnions of

said roller provided with a grooved portion adapted to fit the limited housing entrance during the placing of the roller in position, the roller having been placed within the housing it being impossible for the accidental escapement therefrom. 50

2. In a side bearing, an upper member comprising a base plate and housing, a lower member, a roller interposed therebetween, trunnions formed at the ends of said roller having a grooved portion thereon, said grooved portion allowing the trunnions to pass within a limited entrance to said housing, said base plate provided with raised tooth projections, said lower member provided with a plurality of apertures, said roller provided with raised teeth for a portion of its circumference, said teeth and apertures of the various members adapted to coöperate. 55

3. In a side bearing, an upper member, a lower member, a roller interposed therebetween, the upper member comprising a base plate, walls extending therefrom, said walls provided with longitudinal recesses closed 70 at one end and having a limited opening at their other, trunnions at the ends of said roller having a grooved portion allowing the roller to pass between the said walls and the trunnions into said longitudinal recesses, 75 said upper base plate provided with raised teeth, said lower member provided with a plurality of apertures, said depression being extended through the entire lower member, thereby preventing any accumulation of foreign material therein, said roller provided with raised teeth and apertures engaging the teeth and said apertures of said upper and lower members. 80

This specification signed and witnessed 85 this 29th day of June A. D. 1912.

GEORGE L. ALLEN.
